UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

WEFT-SUPPLYING MECHANISM FOR AUTOMATIC WEFT-REPLENISHING LOOMS.

No. 923,457.

Specification of Letters Patent.

Patented June 1, 1909.

Application filed January 21, 1909. Serial No. 473,514.

To all whom it may concern:

Be it known that I, EDWARD S. STIMPSON, a resident of Hopedale, in the county of Worcester and State of Massachusetts, have 5 invented certain new and useful Improvements in Weft-Supplying Mechanism for Automatic Weft-Replenishing Looms, of which the following is a specification.

The object of the present improvements 10 is to provide an automatic weft-replenishing loom with a magazine containing spare weft-carriers which shall have large capacity as compared with the magazines which are now in commercial use. This large magazine 15 involves special means for taking care of the weft ends and the present improvements consist also in the means for so doing.

One embodiment of the present improvements is illustrated in the accompanying 20 drawings in which:

Figure 1, is a side view of an automatic weft-replenishing loom illustrating the present invention, only so much of the loom being shown as is necessary for an understanding 25 of the invention. Fig. 2, is a side view of the lower part of the loom showing a portion of the magazine for spare weft-carriers. Fig. 3, is a top view of the weft-supplying mechanism. Fig. 4, is a plan view, partly in horizontal section, of the weft-supplying mechanism. Figs. 5, and 6, are side views of portions of the weft-supplying mechanism showing the parts in different periods of action. Fig. 7, is a vertical cross-section in the plane 30 indicated by the line 7—7 in Fig. 3. Fig. 8, is a vertical cross-section in the plane indicated by the line 8—8 in Fig. 3. Figs. 9, 10 and 11 are detailed views of the weft-end holder.

40 There is shown in Fig. 1 the transerrer A which is employed in the well-known Draper loom (as shown, for example, in United States Letters Patent No. 529,940, November 27, 1894,) and which acts in its well-known way to perform its functional movements whenever the exigencies of the loom require the replenishment of the weft. As is customary in the Draper loom, and as shown in the illustrated embodiment of the 45 present improvements, the functional action of the transerrer is to force a spare weft-carrier downwardly into the working shuttle of the loom, and hence into weaving position. The transerrer swings from the position

shown in Fig. 5, to that shown in Fig. 6, 55 thereby transferring a weft-carrier B into the shuttle C and concurrently ejecting the spent weft-carrier downwardly from the shuttle. These figures simply illustrate the position which the shuttle approximately occupies at 60 the instant of transfer; nothing more of the known parts of the loom being shown on account of the well-known character of this operation.

The present improvements include (1) a 65 spare weft-carrier magazine of large capacity; (2) a guide-chute leading from the magazine to the transferring position; (3) a feeder which transfers the weft-carriers one by one from the magazine to the chute and 70 moves the weft-carriers along the chute; and (4) means for holding on to the weft-ends throughout their occupancy of both magazine and chute and until each weft-carrier in turn is transferred into working 75 position in the loom. The improvements will be described *seriatim*.

Magazine.—The magazine is a flexible belt D, which is shown as an endless belt of any desired length but which need not be endless 80 but may be of indefinite length. The upper portion of the endless belt is shown in Fig. 1, and the lower portion in Fig. 2. Within reasonable limits, the belt may be as long as desired. It is intended, however, that the 85 belt should be long enough to carry enough spare weft-carriers to feed the loom for an entire day, thus enabling the replenishment of the magazine to be effected when the mill is shut down. The belt passes around two 90 pulleys 20 and 21, the lower pulley being idle and the upper pulley being the driving pulley for moving the belt. The belt is equipped with appropriate open-mouthed retainers E for the respective weft-carriers. 95 The illustrated belt is made of leather and the several retainers are made of elastic wire so as to grasp and hold the weft-carriers at their middles as shown in the drawings. Each wire retainer is secured to the belt by 100 a cross-plate 22 which is riveted to the belt as shown in Figs. 4 and 7. This construction does not interfere with the flexibility of the belt nor with the firm grip which each retainer has upon its weft-carrier. 105

The belt magazine is moved step by step by the rotation of the driving pulley 20 in the direction indicated by the arrow in Fig. 1.

The advance movement of the belt is derived from a weight 23 and cord 24 extending therefrom over idle pulley 25 to a drum 26 to which it is fastened. This drum is concentric with the upper belt pulley 20, as shown in Fig. 4. This drum has a series of ratchet teeth 27 co-operating with a spring-pressed pawl 28 which is pivoted to the belt pulley 20. Accordingly, as the weight 23 descends, it rotates the belt pulley 20 in the direction of the arrow shown in Fig. 1. Normally, the magazine belt is prevented from movement because one of the weft-carriers which is supported by it comes in contact with fixed stops 29 and 30, as shown in Fig. 7. The weft-carrier butt encounters the stop 29 while the weft-carrier tip encounters the stop 30. Hence, the magazine belt is normally held stationary by one of the weft carriers which it holds. This stopped weft-carrier is in position to be transferred to the guide-chute which leads to the transferring point, and, for identification, it will be called the "active" weft-carrier. As soon as this active weft-carrier is transferred to the guide-chute, the weight 23 causes the magazine belt to advance until the next lower and succeeding weft-carrier on the magazine encounters the stops 29 and 30. Accordingly, the magazine is advanced step by step by the weight as the weft-carriers are successively removed from the magazine. In case the weight requires rewinding, the drum 26 can be turned backwardly by hand, during which movement the pawl 28 rides idly over the ratchet teeth 27. The magazine belt is held from concurrent backward movement by means of a gravity pawl 31 which is pivoted to a fixed part of the loom and engages reversely arranged ratchet teeth 32 (Figs. 1, 3 and 4) on the belt pulley 20. This arrangement also permits the movement of the belt by hand without moving the weight when it is desired to re-fill the magazine. The magazine is very easily and readily supplied with weft-carriers by simply pressing them into the yielding retainers E. To facilitate getting the weft-carriers in the right places in the retainers a fixed guide-plate 33 is employed along a portion of the pathway of the belt against which the butts of the weft-carriers are thrust as they are inserted.

Guide-chute.—A guide-chute leads from the neighborhood of the magazine stops 29 and 30 to the transfer point as indicated in Figs. 4, 5, and 6. This guide-chute, as shown, extends horizontally. It comprises a guide F for the butts of the weft-carriers and a guide G for their tips. As best shown in Fig. 8, the butt guide F embraces the weft-carrier butts sufficiently to prevent any substantial longitudinal movement of the weft-carriers while at the same time permitting the free entrance of the weft-carrier butts

thereinto and free movement of the weft-carriers along the guide-chute. The tip guide G supports the tips of the weft-carriers, thereby maintaining the weft-carriers in horizontal position during their occupancy of the guide-chute. The tip guide, also, has certain peculiarities in connection with the weft-end holders which will be referred to when that subject is considered. The weft-carriers are advanced along the guide-chute F, G, until the forward weft-carrier occupies the critical or transferring position beneath the transerrer A, as shown in Fig. 5. At this point the forward weft-carrier is free from the guide-chute. Its butt is supported by the fixed stop 34 and the spring-pressed yielding stop 35 (Fig. 5), while its tip is supported by the customary spring-pressed yielding finger 36. When weft-replenishment is demanded, the transerrer A swings downwardly, thus forcing the forward weft-carrier downwardly into the shuttle C, during which transferring operation the stop 35 and the finger 36 yield to permit the descent of the forward weft-carrier. Concurrently with this transferring action, the several weft-carriers within the guide-chute F, G, are advanced one step, thus bringing a fresh weft-carries to the transferring point, and, in addition, the active weft-carrier is transferred from the magazine belt into the guide-chute while the magazine belt moves forward one step, bringing a fresh weft-carrier against the stops 29 and 30.

Weft carrier feeder.—This transfer of the active weft-carrier from the magazine belt to the guide-chute and the advance of the weft-carriers in the guide-chute is effected by an automatic feeder H. This feeder is pivotally connected at 37 to an upwardly extending arm 38 which is rigidly connected with the transerrer A so as to swing therewith. When the transerrer swings down to effect a transfer the feeder is moved backwardly as shown in Fig. 6. When the transerrer again rises the feeder is moved forward. The feeder is forked and hooked at its rear end as shown in Figs. 4 and 5, thus providing two hooks 39 adapted to engage the active weft-carrier at two different parts of its length. When the feeder is moved to the rear from the normal position shown in Fig. 5, the beveled lower faces of its rear hooks ride upon and over the adjacent active weft-carrier on the magazine belt. The hooks pass behind the active weft-carrier, whereupon the hooks drop down back of this weft-carrier as shown in Fig. 6. Then, when the transerrer ascends the feeder is drawn forward, thus pulling the active weft-carrier from the magazine belt forwardly into the guide-chute F, G, and, at the same time, forcing forward the series of weft-carriers occupying the guide-chute until the forward weft-carrier comes against the yielding stop 35.

Certain details of the feeder are important. As shown in Figs. 5 and 6, the feeder is composed of two telescoping parts held together by a spring 40. This spring yields in case of the occurrence of any contingency which might be apt to cause breakage. The feeder is maintained in its normal position by gravity. The action of gravity, however, may be too sluggish to cause the feeder hooks to promptly descend when back of the active weft-carrier in the magazine belt. To insure the prompt descent of the feeder hooks at this time, there are provided two spring-pressed plungers I, I, best shown in Fig. 7, which are directly above the two feeder hooks 39. These plungers are normally out of contact with the hooks as shown in Figs. 5 and 7; but, when the hooks rise in passing back of the active weft-carrier in the magazine belt, they come in contact with these plungers, lifting them, and compressing their springs, so that the hooks are quickly pressed down when they get back of the active weft-carriers.

Taking care of weft-ends.—Each weft-carrier is provided with its own detachable weft-end holder J which in its broad aspects is similar to the weft-end holder of United States Letters Patent No. 860,703 of Melvin L. Stone, July 23, 1907. In the present instance, however, the holder J is provided with yielding fingers 41 which enter the central bore of a weft-carrier and yieldingly retain the holder on the tip end of the weft-carrier. A thread-slot 42 permits the passage of the weft-end to the outwardly extending thread stud 43, thereby keeping the thread away from the exterior of the holder J so that there is no danger of any rubbing of the thread. These thread holders retain the weft-ends throughout the occupancy of the weft-carriers of their positions in the magazine and the guide-chute and until the weft-carriers are transferred into weaving position in the loom. It is necessary, however, that each weft-end holder should be detached from its weft-carrier prior to the transfer of the weft-carrier to the loom; but, that said holder should hold onto the weft-end during the first traverse of the transferred weft-carrier through the shed. For this purpose the tip guide G of the guide-chute is provided with a cam-track K, which is best shown in Figs. 4 and 8, this cam-track extending along-side the chute. When a weft-carrier is transferred from the magazine belt to the guide-chute its weft-end holder enters the mouth of this cam-track. Then, as the weft-carrier is advanced step by step along the guide-chute its weft-end holder is cammed gradually outwardly, as shown in Fig. 4, until it is wholly separated from its weft-carrier when the weft-carrier reaches the transferring position. At this point, however, the weft-end holder still occupies a

definite relation to its weft-carrier and maintains its hold on the thread so that the thread is drawn out during the first passage of the transferred fresh weft-carrier through the shed. After a transfer has been effected, the detached weft-end holders are shoved gradually ahead by those in the rear until they reach the forward end of the cam-track K whence they drop into any suitable receptacle. A flanged cover I (Figs. 1, 3 and 8) overlies the cam-track K and its flange 44 is correspondingly cam-shaped so as to facilitate the detachment of the holders from the carriers. This cap also prevents any undue rising of the weft-end holders. This camming action can not move the weft-carriers themselves endwise to any substantial extent by reason of the butt guide F which embraces the butts sufficiently for this purpose as shown in Fig. 8.

It is desirable that there should be some slack thread available between the weft-carrier and the weft-end holder when the weft-carrier is transferred to the lay, and this can be provided by laying the weft-end in a loop on the body of weft, as indicated at 45, in Fig. 8; this loop extending from the body of the weft to the holder J.

I claim:

1. An automatic weft-replenishing loom having, in combination, an endless flexible belt having a plurality of open-mouthed yielding retainers, each for a weft-carrier having a detachable weft-end holder at its tip; a weight acting to move said belt in one direction; fixed stops which engage the active weft-carrier on the belt and thereby prevent forward movement of the belt; a guide chute leading from the belt to the transfer point; a cam-track alongside the guide chute and engaging the weft-end holders, said cam-track extending beyond the transferring point; a transerrer for transferring a weft-carrier into weaving position; and a feeder operatively connected with the transerrer, and acting to feed the weft-carriers one by one from the belt to the guide chute and to feed the weft-carriers along the guide chute to the transfer point, during which feeding movement along the guide chute the cam-track removes the weft-end holders from the weft-carriers.

2. An automatic weft-replenishing loom having, in combination, an endless flexible belt having a plurality of open-mouthed yielding retainers each for a weft-carrier; a weight acting to move said belt in one direction; fixed stops which engage the active weft-carrier on the belt and thereby prevent forward movement of the belt; a guide chute leading from the belt to the transfer point; a transerrer for transferring a weft-carrier into weaving position; and a feeder operatively connected with the transerrer, and acting to feed the weft-carriers one by one

from the belt to the guide chute and to feed the weft-carriers along the guide chute to the transfer point.

3. An automatic weft-replenishing loom 5 having, in combination, a belt having a plurality of retainers each for a weft-carrier; means acting to advance said belt; fixed stops which engage the active weft-carrier on the belt and thereby prevent forward movement of the belt; a guide chute leading from the belt to the transfer point; a transerrer for transferring a weft-carrier into weaving position; and a feeder acting to feed the weft-carriers one by one from the belt to the 10 guide chute and to feed the weft-carriers along the guide chute to the transfer point.

4. An automatic weft-replenishing loom having, in combination, a magazine carrying a plurality of weft-carriers; means acting to 20 move said magazine step-by-step at each transfer of a weft-carrier into weaving position; a guide chute leading from the magazine to the transfer point; a transerrer for transferring a weft-carrier into weaving position; 25 and a positively actuated feeder acting to feed the weft-carriers one by one from the magazine to the guide chute and to feed the weft-carriers along the guide chute to the transfer point.

30 5. An automatic weft-replenishing loom having, in combination, a flexible magazine having a plurality of retainers, each for a weft-carrier; a weight acting to move said magazine forward; fixed stops which engage the active weft-carriers on the magazine and thereby prevent forward movement of the magazine; and a feeder acting to feed the 35

weft-carriers one by one from the magazine to the transfer point.

6. An automatic weft-replenishing loom 40 having, in combination, a movable magazine carrying a plurality of weft-carriers, each having a detachable weft-end holder at its tip; a guide chute leading from the magazine to the transfer point; a cam-track alongside 45 the guide chute and engaging the weft-end holders; a transerrer for transferring a weft-carrier into weaving position; and a positively actuated feeder acting to feed the weft-carriers one by one from the magazine 50 to the guide chute and to feed the weft-carriers along the guide chute to the transfer point, during which feeding movement along the guide chute the cam-track removes the weft-end holders from the weft-carriers. 55

7. An automatic weft-replenishing loom having, in combination, a guide chute for weft-carriers, each having a detachable weft-end holder at its tip; a cam-track alongside 60 the guide chute and engaging the weft-end holders; a transerrer for transferring a weft-carrier into weaving position; and a positively actuated feeder acting to feed the weft-carriers along the guide chute to the transfer point, during which feeding move- 65 ment the cam-track removes the weft-end holders from the weft-carriers.

In witness whereof, I have hereunto signed my name in the presence of two subscribing witnesses.
